Primary Examiner — Gino Colan(74) *Attorney, Agent, or Firm* — Dorsey & Whitney LLP(57) **CLAIM**

The ornamental design for a flip-up ladder, as shown and described.

DESCRIPTION

FIG. 1 is a perspective view of a flip-up ladder; FIG. 2 is a front view of the flip-up ladder shown in FIG. 1; FIG. 3 is a rear view of the flip-up ladder shown in FIG. 1; FIG. 4 is a right side view of the flip-up ladder shown in FIG. 1;

FIG. 5 is left side view of the flip-up ladder shown in FIG. 1; and,

FIG. 6 is a top view of the flip-up ladder shown in FIG. 1. The broken lines shown in the figures are for the purpose of illustrating boundaries and form no part of the claimed design.
